Specification of Letters Patent. Patented Oct. 27, 1914.

Application filed February 27, 1913. Serial No. 748,584.

To all whom it may concern:

Be it known that I, JOHN J. HOFFMAN, a citizen of the United States, and a resident of New Kensington, in the county of Westmoreland and State of Pennsylvania, have invented a new and useful Improvement in Car-Roofs, of which the following is a specification.

The invention has for its principal objects to produce an improved seam joint for outside metal roofing sheets, which is absolutely water-proof, yet sufficiently loose and flexible so as to permit considerable relative movement of the sheets to compensate for the weaving of the substructure; to obviate the necessity for employing separate seam caps and incidentally eliminate the securing devices usually required therefor; and to attain certain advantages which will herein-after more fully appear.

In the accompanying drawings which form part of this specification and wherein like symbols refer to like parts wherever they occur, Figure 1 is a fragmentary plan view showing the co-operating seam portions of two roofing sheets in the region of the middle of the roof and at the eaves; Fig. 2 is a transverse section through the roof adjacent to a seam; Fig. 3 is a fragmentary view partly in vertical section and partly in side elevation of a roofing sheet detached; Fig. 4 is a fragmentary perspective view of the co-operating seam portions of two adjoining roofing sheets in the region of eaves ends of the sheets; Fig. 5 is a detail view of one side marginal portion of a roofing sheet in the region of the ridge or crown; Fig. 6 is a similar view of the opposite side marginal portion; and Fig. 7 is a vertical section through the seam at the ridge or crown.

The sheets illustrated in the drawings are of the type which extend entirely across the car from eaves to eaves, and they may be adapted either for a radially curved arched roof or a peaked roof which inclines down to the eaves on opposite sides of the ridge at the middle of the roof.

In the drawings the peaked type of roof is shown. The substructure includes a ridge pole 1 and side plates 2 on which the wooden sheathing 3 is mounted; and it is, of course, understood that suitable carlines or transverse frame members may be employed in the substructure. The ends of the roofing sheets 4 are turned down over the eaves, as at

5. Near one of the side margins, the roofing sheets are reflexed or rebent, as at 6, said reflex portions being pressed close together and bent over toward the margin and down parallel with the body of the sheet but 60 spaced therefrom, as at 7, to provide a horizontal groove; and the extreme marginal portion is flanged upward, as at 8. The opposite marginal portions of the sheets are reflexed or rebent upward, outward and 65 downward as at 9, 10 and 11, to provide a relatively wide hollow high rib; while the extreme marginal portion 12 outside of said rib extends horizontally parallel with the body portion and is preferably rebent or 70 doubled under, as at 13, the under face of said rebent portion being in substantially the same plane as the top face of the body of the roofing sheet.

In assembling the sheets, the high ribbed 75 marginal portions of the respective sheets are lapped over the flanged marginal portions of the adjoining sheets, and the marginal lips or flanges 12 are slipped under the overhanging lips provided by the rebent 80 portions 6. The relative widths of the portions 6 and 12 are so proportioned with respect to the distance between the side walls 9 and 11 of the high rib and the distance between the edge of the portion 6 and flange 8, 85 that the portion 12 may be dropped readily between the edge of said portion 6 and said flange 8 and then slid under said portion 6. That is, the distance between the flange 8 and the edge of the lip 6 must be such that 90 the part of the member 12 which underlies the said lip 6 may be withdrawn clear thereof. In practice, when the sheets are applied on the roof, the wall 9 of the ribbed portion of the one sheet should be spaced normally 95 one-eighth of an inch from the flange 8 of the adjoining sheet, and the opposite side wall 11 of the rib should be spaced from the edge of the lip 6 a little greater distance, and the edge of the portion 12 from end of the 100 groove 7 a still greater distance, so that the two sheets may move together until only the flange 8 and side wall 9 contact. Any water that may percolate or be driven in under the lip 12, is quickly conducted off in 105 the channel provided between the wall 11 and flange 8. This channel being of so much greater area than the space between the lip 6 and said lip 12, the water will not bank up against the flange 8 so as to flow 110

over the upper edge thereof, but will run off in the channel as fast as it enters. Furthermore, by reason of the lip 12 resting normally on the adjacent roof sheet, and there being a space between the edge of the portion 12 and end of the groove 7, the water, unless driven with considerable force, will flow down said groove 7 and out at the eaves. To prevent the water which may run down the groove 7 from backing up at the eaves, the portions of the lip 6 which are turned down over the eaves are perforated, as at 6^a, to provide a free outlet.

The roofing sheets are secured at the eaves by clips or castings 14 having hood portions 15 adapted to fit loosely over the ribs so as to permit a limited movement to the sheets; while at intervals between the seams the sheets may be retained by the ordinary clips. At the center of the car the seam ribs are perforated and preferably flanged upward, as at 16, adjacent to the wall 9, for the passage therethrough of the bolt 17 which secures the running board saddle 18 in place; and the adjacent portion of the flange 8 of the adjoining roof sheet is correspondingly indented, as at 19. It is, of course, understood that the indented portion 19 of the flange 8 is spaced from the other wall 11 of the rib a distance sufficient to permit the portion 12 to be slipped into and out of place under the lip 6.

In order to stiffen the hollow ribbed portions of the roofing sheets, the top and side walls of the ribs are corrugated at intervals throughout the length of the sheet, the corrugations 20 in the top wall extending preferably diagonally and the respective vertical corrugations 21 in the side walls being continuations of said top corrugations. The corrugations are located relatively close to each other so that a person walking on the roof will not be liable to tread between the corrugations on top of the ribs. That is, the adjacent ends of the respective corrugations are so close together that should a person tread directly between them, the sole of his shoe will lap over the ends of two adjacent corrugations. These corrugations while preventing the top wall from being crushed in, also prevent the side walls from spreading or collapsing.

Obviously the structure admits of considerable modification without departing from the invention, therefore I do not wish to be limited to the exact construction and arrangement shown.

What I claim is:

1. A car roof comprising movably mounted metal sheets bent intermediate their ends and connected by loose waterproof seams, said roof sheets being partly over and partly under their fellows, the under parts having upstanding flanges along the margins thereof and doubled up folds in said

sheets parallel with and reflexed toward said flanges forming overhanging lips spaced therefrom, the tops of said lips being lower than the tops of said upstanding flanges, and the upper parts lapping over said under parts and consisting of inverted channels with outwardly projecting flanges along the lower edges of their side walls, said channels straddling over said upstanding flanges and having their side walls spaced therefrom, the outwardly projecting flanges of said channels underlying the overhanging lips of said sheets, the clear width within said inverted channels between their side walls and the upstanding flanges of the under parts of said sheets upon which said side walls respectively rest being greater than the width of the respective portions of the projecting flanges underlying the overhanging lips of said sheets, whereby intermediate sheets can be assembled and removed singly from the roof by vertical and sidewise movements.

2. A car roof comprising movably mounted metal sheets bent intermediate their ends and connected by loose waterproof seams, said roof sheets being partly over and partly under their fellows, the under parts having upstanding flanges along the margins thereof and doubled up folds in said sheets parallel with and reflexed toward said flanges forming overhanging lips spaced therefrom, and the upper parts lapping over said under parts and consisting of inverted channels with outwardly projecting flanges along the lower edges of their side walls, said channels straddling over said upstanding flanges and having their side walls spaced therefrom, the outwardly projecting flanges of said channels underlying the overhanging lips of said sheets, the clear width within said inverted channels between their side walls and the upstanding flanges of the under parts of said sheets upon which said side walls respectively rest being greater than the width of the respective portions of the projecting flanges underlying the overhanging lips of said sheets, whereby intermediate sheets can be assembled and removed singly from the roof by vertical and sidewise movements.

3. A car roof comprising movably mounted metal sheets connected by loose waterproof seams, said roof sheets being partly over and partly under their fellows, the under parts having upstanding flanges along the margins thereof and doubled up folds in said sheets parallel with and reflexed toward said flanges forming overhanging lips spaced therefrom, and the upper parts lapping over said under parts and consisting of inverted channels with outwardly projecting flanges along the lower edges of their side walls, said channels straddling over said upstanding flanges and having their

- side walls spaced therefrom, the outwardly projecting flanges of said channels underlying the overhanging lips of said sheets, the clear width within said inverted channels 5 between their side walls and the upstanding flanges of the under parts of said sheets upon which said side walls respectively rest being greater than the width of the respective portions of the projecting flanges underlying the overhanging lips of said sheets, whereby intermediate sheets can be assembled and removed from the roof without removing the sheets adjacent thereto.
4. A car roof comprising metal sheets 15 movably mounted on the substructure, said sheets being turned down over the eaves and connected by loose waterproof seams, said seams comprising an upstanding flange at the margin of a sheet, an overhanging lip 20 formed by reflexing said sheet inward from said flange, said reflex portions extending over the eaves but said flange terminating short of the eaves, the reflex portions having openings therein in the region of the eaves, 25 a relatively wide hollow upstanding rib on the adjoining sheet adjacent to the margin thereof overhanging said marginal flange of said first mentioned sheet, said flange being located adjacent to the inner side wall of 30 said rib, a marginal lip on said second mentioned sheet outside of said rib and underlying the overhanging lip portion of said first mentioned sheet.
5. A car roof comprising movably mounted metal sheets connected by loose waterproof seams, said seams comprising an upstanding flange at the margin of a sheet, an overhanging lip formed by a reflexed fold of 35 said sheet spaced inward from said flange, a relatively wide hollow upstanding rib on the adjoining sheet adjacent to the margin thereof, and a marginal lip on said second mentioned sheet outside of said rib, the margin of said second sheet lapping over said first 40 sheet with said hollow rib straddling said marginal flange of said first mentioned sheet, and said marginal lip underlying said overhanging lip portion on said first mentioned sheet, the clear width of said rib between the 45 inner side wall and said marginal flange being greater than the width of the portion of 50 said marginal lip underlying said overhanging lip.
6. A metal car roof comprising a plurality of like roof sheets extending transversely of the car from eaves to eaves and lapped along their margins, the edge of the under sheet being formed at its center with a flanged notch and the overlapped margin of
- the upper sheet being formed with a flanged 60 hole in vertical alignment with said notch, and a retaining bolt extending through said hole and engaging said notch whereby said sheets are held from movement crosswise of the car and said upper sheet is held from 65 movement lengthwise of the car.
7. A metal car roof comprising a plurality of like roof sheets extending transversely of the car from eaves to eaves and lapped along their margins, one edge of a sheet lapping 70 over the sheet adjacent thereto and the opposite edge of said sheet lapping under the sheet adjacent thereto, the under edge of each of said sheets being formed at its center with a flanged notch and the overlapped 75 margin of each of said sheets being formed with a flanged hole, said sheets being arranged with their flanged holes in vertical alignment with said notches, and retaining bolts at the ridge of the car extending 80 through said holes and engaging said notches whereby said sheets are pivotally secured to the car at the ridge at one margin and are held from movement crosswise of the car at the opposite margin of each. 85
8. In a car roof, the combination with the substructure, of metal sheets movably mounted on said substructure, said sheets extending from eaves to eaves and being connected at their side margins by loose waterproof seams, said seams comprising an upstanding flange at one margin of a sheet, an overhanging lip adjacent to said upstanding flange, said lip being formed by crimping the sheet upward and bending said 90 crimped portion outward and downward, the adjoining sheet having a reflex portion near its margin providing an upstanding relatively wide hollow rib adapted to straddle said upstanding flange of the adjoining 100 sheet, and the marginal portion of the sheet outside of said rib constituting a lip adapted to fit under said overhanging lip on said adjoining sheet, said upstanding flange being located normally near the inner side 105 wall of said rib, said rib having a bolt opening in its top wall adjacent to said inner side wall, and the adjacent body portion and upstanding flange of the adjoining sheet being correspondingly indented in the region of said bolt opening. 110

Signed at St. Louis, Missouri, this 15th day of February, 1913.
